UNITED STATES PATENT OFFICE

162,738

KNOB FOR COOKING UTENSILS AND THE LIKE

James L. Hvale, Chicago, Ill., assignor to Ekco
Products Company, Chicago, Ill., a corporation
of Illinois

Application January 14, 1949, Serial No. 236

Term of patent 7 years

(Cl. D44—29)

To all whom it may concern:

Be it known that I, James L. Hvale, a citizen of the United States, residing at Chicago, county of Cook, State of Illinois, have invented a new, original, and ornamental Design for a Knob for Cooking Utensils and the like, of which the following is a specification, reference being had to the accompanying drawing, forming part thereof.

Fig. 1 is a side elevational view of a knob for cooking utensils showing my new design.

Fig. 2 is a top plan view.

Fig. 3 is an end elevational view thereof.

Fig. 4 is a vertical sectional view through the knob taken on line 4—4 of Fig. 1.

I claim:

The ornamental design for a knob for cooking utensils and the like, as shown.

JAMES L. HVALE.
